UNITED STATES PATENT OFFICE.

WILLIAM MARLOW, OF NEW YORK, N. Y., ASSIGNOR TO STANDARD KNITTING MILLS COMPANY, A CORPORATION OF NEW YORK.

METHOD OF MAKING UNION GARMENTS.

1,132,666.

Specification of Letters Patent. Patented Mar. 23, 1915.

Application filed July 8, 1913. Serial No. 777,825.

To all whom it may concern:

Be it known that I, WILLIAM MARLOW, a citizen of the United States, and a resident of the borough of Brooklyn, city of New York, county of Queens, and State of New York, have invented certain new and useful Improvements in Methods of Making Union Garments, of which the following is a specification.

10 My invention has for its object a method of making union garments whereby they may be easily, cheaply and simply manufactured, and has particular reference to the manufacture thereof from tubular knitted fabrics.

15 A further object of my invention is a method of making a garment of the class described, in which horizontal seams shall be as nearly as possible eliminated, and the 20 number of seams greatly reduced.

25 A further object of my invention is to produce a garment which shall be completely closed in front and at the same time have overlapping flaps at the back, so made 30 that the garment will tend to remain closed.

In the drawings accompanying my specification, I have shown in Figure 1 a front view of my improved garment, and in Fig. 2 a back view thereof. In Fig. 3 I have 35 shown, in a more or less diagrammatic way, the method of cutting the tube used.

Referring to Fig. 1, it will be seen that the garment is divided vertically or longitudinally by a seam 1-2, which extends 40 from the neck to the crotch.

Referring to Fig. 2, it will be seen that the seams at the back are a horizontal seam, 3-4, extending across the middle of the back and securing the flaps to the body of 45 the garment, and a vertical seam, 5-6, extending from the neck to the horizontal or transverse seam.

In carrying out my improved method, I take a tube of knitted material, such as that 50 ordinarily produced upon a cylinder knitting machine, and make two transverse cuts, 7-8 and 9-10, therein. These transverse cuts are joined by a longitudinal cut, 9-8. This gives two L-shaped pieces, of 55 which one corner is removed by a long diagonal cut, 9-11 and 8-12. The corresponding corners of the L-shaped pieces at the back of the tube are cut off as at 13-14

and 15-16. The pieces thus shaped are reversed and overlapped so that the front 55 seam, 1-2, is formed at the juncture of edges 9-8 of both pieces, and of edges 9-11 with edges 8-12, the crotch being formed where the points 11 and 12 meet. By reason of the diagonal form of edges 60 8-12 and 9-11, the garment is given a flare at the bottom, thus properly shaping it. In reversing one of the L-shaped pieces with reference to the other, the flaps included within the lines 12, 16, 15, 8 and 14, 65 13, 9 and 11, overlap, thus forming overlapping flaps at the back of the garment. These flaps are secured together, and to the body of the garment, by sewing their upper edges, 15-8 and 9-13, together and to the 70 body of the garment by the horizontal seam 3-4.

I am aware that the exact method described may be varied without departing from the spirit of my invention, and I therefore do not intend to confine myself to the exact form shown and described.

What I claim is:

The method of making a union garment from a piece of tubular fabric which consists in forming two transverse cuts extending inwardly at right angles from the edges to the center on one side of the tube, forming two oppositely inclined cuts from the center to the outer edges on the other side 85 of the tube, forming a longitudinal cut on both sides of the tube joining the transverse cut and apices of the inclined cuts, reversing the portions so cut, joining the inclined cuts and longitudinal cuts on that side of 90 the tube to form a single continuous straight front seam running from the crotch to the neck opening, joining the longitudinal cuts on the other side to form a central back seam, overlapping the transverse cuts on 95 each side of the center back seam, and joining the edge of each transverse cut to the opposite portion by a single horizontal seam.

In witness whereof I have hereunto set 100 my hand in the presence of two witnesses this 7th day of July, 1913.

WILLIAM MARLOW.
